[57] CLAIM

The ornamental design for a combined notebook and separator pages therefor, as shown and described.

DESCRIPTION

FIG. 1 is a front perspective view of a combined notebook and separator pages therefor showing our new design;

FIG. 2 is a reduced scale top plan view thereof;

FIG. 3 is a reduced scale bottom plan view thereof;

FIG. 4 is a top elevational view thereof;

FIG. 5 is a rear elevational view thereof;

FIG. 6 is a right side elevational view thereof;

FIG. 7 is a left side elevational view thereof;

FIG. 8 is a reduced scale top plan view thereof, in a fully opened position; and,

FIG. 9 is a reduced scale top plan view thereof, in a fully opened position, showing the separator pages with top tabs only for clarity of illustration only.

The top tab portions of the separator pages shown in FIGS. 1, 8 and 9 are shaded to indicate color.

The broken lines shown in FIGS. 1, 2, 3, 8 and 9 represent conventional stitching.
